Atty.

UNITED STATES PATENT OFFICE.

JACOB S. BROWN, OF CARLISLE, PENNSYLVANIA, ASSIGNOR OF ONE-HALF
TO WILLIAM E. AND JOHN R. MILLER, OF SAME PLACE.

MECHANICAL MOVEMENT.

SPECIFICATION forming part of Letters Patent No. 367,888, dated August 9, 1887.

Application filed January 18, 1887. Serial No. 224,727. (No model.)

To all whom it may concern:

Be it known that I, JACOB S. BROWN, a citizen of the United States, residing at Carlisle, in the county of Cumberland and State of Pennsylvania, have invented certain new and useful Improvements in Mechanical Movements; and I do hereby declare the following to be a full, clear, and exact description of the invention, such as will enable others skilled in the art to 10 which it appertains to make and use the same.

My invention relates to mechanical movements, and particularly to double-acting cranks convertible into single-acting cranks; and it consists in the construction and arrangement 15 of the parts of the same, which will be more fully hereinafter described, and pointed out in the claims.

One object of my invention is to provide a crank which has a double stroke to one revolution of the wheel in which it is mounted, and which is specially adapted for use in connection with all kinds of well-drilling machines.

A further object of my invention is to provide 25 a double-acting crank which is convertible into a single-acting crank, which is simple and effective in construction and operation, strong and durable, easily handled and operated, readily understood, positive in its design, and cheap in its manufacture.

I attain these objects by the device illustrated in the accompanying drawings, wherein like letters of reference indicate similar parts 35 in the several views, and in which—

Figure 1 is a front elevation of my improved crank, with a portion thereof broken away. Fig. 2 is a detail view in side elevation of the internal mechanism or angle-block.

40 A indicates a wheel of ordinary form of construction, which may have a plane periphery or be provided with cogs, as may be desired, and which has an annular recess formed in one side and adapted to be mounted upon a shaft 45 in connection with any desired machine with which it is applicable to use the same.

An angle-block, B, is mounted in the annular portion of the wheel A, and secured on the end of the shaft thereof by means of a cap-plate, b, and a screw, b', passing through said cap-plate and angle-block and into the shaft,

upon which they are mounted. The angle-block B is constructed of metal, and is cast with two projecting arms, 1 and 2, which extend outward at right angles or nearly right angles to the shaft and to themselves, and uniting in an elbow which is secured to the shaft, as heretofore described. The outer ends, 3 and 4, of the said arms 1 and 2 engage with the inner periphery of the wheel A, and the 55 lower portion of each of said arms 1 and 2 have shoulders 5 and 6 formed therewith, which are provided with recesses or mortises, for a purpose which will be more fully hereinafter described.

65 Two arms, 7 and 8, are constructed, which are provided with enlarged outer ends, 9 and 10, which are also adapted to engage with the inner periphery of the wheel A. The arms 7 and 8 are formed with tenons at their lower 70 portions, which are adapted to enter the recesses or mortises formed in the shoulders 5 and 6, and pivotally secured therein by the pivots 11 and 12. The arm 7 is provided with a series of two or more apertures, 13, with 75 which a removable wrist-pin, 14, engages, and secured therein by suitable means, and, as shown in the drawings, is mounted in the upper aperture of said series. By means of this removable wrist-pin 14 the stroke of the crank can be 80 readily adjusted to different lengths, as may be desired, and which will be readily understood.

85 The arm 8 is of smaller dimensions than the arm 7, and acts as a back-stop to prevent the backward motion of the entire angle-block B. Between the inner rear side of the said arm 8 and the outer side of the arm 2 a flat spring, 15, is interposed, the lower portion of which rests in the recess formed in the shoulder 6, 90 and the outer end thereof engages with a small shoulder, 16, formed on the outer inside portion of the arm 8. By means of this spring 15 the arm 8 is held out slightly away from the arm 2, and is caused to impinge against the 95 inside periphery of the wheel A.

The arm 7 is supported only by the pivot 11, and is constructed to normally lie close to the arm 1. Adjacent to the upper portions of each of the arms 1 and 2 screws 17 and 18 pass 100 through the said arms, having entrance therein from the sides thereof opposite to the sides

adjacent to the arms 7 and 8. The normal operation of the angle-block B is in the direction of the arrow, as shown in the drawings, the said block being prevented from slipping 5 in the reverse direction by the binding of the outer ends of the arms 7 and 8 against the periphery, and especially of the spring-actuated arm 8, which bears continually upon the said periphery. By causing the screws 17 and 18 10 to impinge against the two arms 7 and 8 they are forced away from the arms 1 and 2, and the outer ends of the said arms 7 and 8 are forced to bear firmly against the inner periphery of the wheel A, thereby converting the device 15 into a single-acting crank. When the block B, of the construction heretofore described, is mounted on the shaft of a suitable wheel, A, a thin metallic ring-plate, C, is secured on the side of the wheel A, by means of 20 the screws c, over the said block B, and in such a manner that it will slightly project inward over the inner periphery of the wheel and form a flange which acts to retain the said block B in its relatively operating position in 25 the wheel A.

The outer periphery of the wheel A may be provided with a cogged surface, and thereby adapted to mesh with suitable gearing, and power applied through the medium thereof to 30 the said wheel A.

In the use of this device, in connection with rock and oil-well drilling machinery the drill-rope D will be attached directly to the wrist-pin 14, and pass thence over a small sheave or 35 pulley placed in the frame-work of the machine in any suitable position above said wrist-pin. As the wheel A is revolved by its shaft, the angle-block B revolves therewith until it reaches about the point diametrically 40 opposite to the position of the said block, as shown in Fig. 1, when it will slide forward to the position shown in said figure. This sliding movement of the angle-block B occurs at each half-revolution of the wheel A, thus giving 45 two drops to a single revolution of the said wheel. By this means an effective double-acting crank is secured, which is specially useful in connection with all kinds of well-drilling machinery, as the drill motion is increased thereby to just double the speed now 50 given by the constructions generally used.

It will be understood that the outer enlarged ends of the arms 1, 2, 7, and 8 in the operation of a double stroke just touch the inner periphery of the wheel A and freely slide in 55 the channel or groove formed by the said inner periphery and the plate C.

The wheel entire and the angle-block B move or revolve in the direction of the arrow; but 60 the angle block B slides forward when it reaches a point diametrically opposite to that shown faster than the wheel revolves and assumes its former position on the wheel, as represented. This is accomplished through the 65 medium of the drill rope or pitman D, adapted to be secured to the wrist-pin 14, as follows: When the wheel A starts to revolve, the block

B also moves in the same direction, and the rope or pitman D, drawing upward on the wrist-pin 14, causes the arm 7 to bind against 70 the inner periphery of the wheel A by slightly pulling it away from the arm 1. The pitman or rope D continues to draw upward on the wrist-pin 14, and causes an impingement of the outer end of the arm 7 against the inner 75 periphery of the wheel A until a point diametrically opposite to the starting-point, as shown, is reached, when the said arm 7 is drawn forward against the arm 1, and when thus released there is no binding between the 80 inner periphery and any of the arms of the block B, and the block entire will slide forward to the starting-point, moving in the same direction that the wheel is revolving, but at a much more rapid rate of speed. When the 85 starting-point is reached, the arm 7 is again impinged against the periphery of the wheel, and the same operation is the result. The arm 8 acts merely as a brake to prevent the block B from slipping backward, which is due to 90 the action of the spring 15 pressing the said arm outward and causing it to bear against the periphery of the wheel A. When there is a tendency on the part of the arm 8 to slide 95 backward, the outer end thereof impinges against the periphery of the wheel and stops this tendency; but when the block B moves in the direction of the arrow the arm 8 is pressed 100 inward against the arm 2, and the outer end of the said arm 8 is disengaged from the periphery of the wheel, and thus the block freely slides, as before set forth.

In converting this device into a single-acting crank, the screws 17 and 18 are caused to impinge against and force the arms 7 and 8 105 outward away from the arms 1 and 2 of the block B and force them firmly against the inner periphery of the wheel A, thereby preventing the block B from slipping on the half-revolution, as heretofore described, but turning 110 with the wheel A in its entire revolution.

It is obvious that many minor changes in the construction and arrangement of the parts could be made and substituted for those shown and described without in the least departing 115 from the nature and principle of my invention.

Having thus described my invention, what I claim as new, and desire to secure by Letters Patent, is--

1. In a double-acting crank convertible into a single-acting crank, the combination of a wheel adapted to be mounted on a shaft, an angle-block having arms mounted in said wheel, and means, as set forth, for securing the several parts, substantially as described.

2. In a double-acting crank convertible into a single-acting crank, the combination of a wheel mounted upon a shaft, an angle-block provided with arms mounted in said wheel and upon the shaft thereof, movable arms pivotally mounted in recesses in said angle-block and adapted to engage with the inner surface of the rim of the wheel, and means, as set forth,

for securing the several parts, substantially as described.

3. In a double-acting crank convertible into a single-acting crank, the combination of a wheel mounted upon a shaft, an angle-block provided with arms adapted to engage with the inner periphery of and mounted in said wheel and upon the shaft thereof, suitable recessed shoulders formed on said angle-block, arms pivotally mounted in said recesses and engaging with the inner surface of the rim of the wheel, a spring interposed between one of the said arms and one arm of the angle-block, and a ring-plate for securing the angle-block in the wheel, substantially as described.

4. In a double-acting crank convertible into a single-acting crank, the combination, with a wheel, of an angle-block provided with arms mounted in said wheel and upon the shaft thereof, arms 7 and 8, mounted in recesses in the angle-block shoulders, and screws 17 and 18, passing through the said angle-arms and

adapted to impinge against the arms 7 and 8 and convert the crank from a double to a single acting crank, substantially as described. 25

5. In a double-acting crank convertible into a single-acting crank, the combination of a wheel, A, mounted on a shaft, an angle-block, B, having arms 1 and 2, and provided with recessed shoulders 5 and 6, mounted in said wheel A and upon the shaft thereof, arms 7 and 8, pivotally mounted in said recessed shoulders 5 and 6 and engaging at their outer ends with the inner surface of the rim of the wheel A, a spring, 15, interposed between the arms 2 and 8, the screws 17 and 18, and the ring-plate C, all arranged and operating substantially as described.

In testimony whereof I affix my signature in presence of two witnesses.

JACOB S. BROWN.
